BASCULE BRIDGE

Heinrich Breitwieser, Griesheim, near Darmstadt, Germany, assignor to Maschinenfabrik Augsburg-Nuernberg A. G., Nuremberg, Germany, a corporation of Germany

Application October 20, 1933, Serial No. 694,392
In Germany October 15, 1932

4 Claims. (Cl. 14—40)

My invention relates to operating means for bascule bridges and equivalent swinging structures, and has generally in view to provide an operating means which may, at comparatively small expense, be mounted in a solid foundation in the ground below the level of the bridge floor; which occupies comparatively little space; which includes an actuator in the advantageous form of a rack bar connected to the bridge by a push-pull rod as distinguished from an actuator in the form of a crank or the like, yet which possesses the advantages of a crank actuator respecting slow initiation of movement of the bridge toward open and closed positions and gradual reduction of the speed of the bridge as it approaches said positions; and which includes rack bar guide means having portions which, respectively, are disposed in alinement with and substantially at right angles to the push-pull rod when the bridge is in open and closed positions, whereby the bridge is securely held in such positions.

With the foregoing and other objects in view, as will become more fully apparent as the nature of the invention is better understood, the same consists in the novel combination and arrangement of features as will be hereinafter more fully described, illustrated in the accompanying drawings and defined in the appended claims.

In the accompanying drawings:

Figure 1 is a diagrammatic side elevation of a bascule bridge illustrating the present operating means applied thereto.

Figures 2 and 3 are cross sections on the lines 2—2 and 3—3, respectively, of Figure 1.

Figure 4 is a detail view illustrating a slight modification of the structure shown in Figure 1.

Figure 5 is a view similar to Figure 1 illustrating an alternative embodiment of the invention; and

Figures 6 and 7 are cross sections on the lines 6—6 and 7—7, respectively, of Figure 5.

Referring first to the Figures 1 to 3 embodiment of the invention, 10 designates, generally, a bascule bridge of a known type having at one end thereof a sector 11 to be rolled upon a surface x to effect swinging movement of the bridge between raised or open and lowered or closed positions.

Pivotedly connected at one end to the bridge, as at 12, coaxially with the axis of curvature of the sector 11, is a push-pull rod 13 which, at its other end, is pivotally connected, as at 14, to a rack bar 15 preferably at a point midway, or approximately midway, between the ends of said rack bar. The rack bar is of the flexible type comprising a plurality of links 15' pivotally con-

nected together in end to end relationship, and on some or all of the pivot pins which connect said links are mounted rollers 16 which travel in channel-like guide members 17.

The guide members 17 are disposed below the surface x and may very readily, cheaply and easily be mounted firmly and solidly in the ground by means of concrete foundations or in any other suitable manner. Generally, they are horizontally disposed. They are, however, of stepped 10 formation to provide relatively short inclined portions 18 and 19 which, respectively, are disposed so as to aline with and extend at substantially right angles to the push-pull rod 13 when the bridge is in open and closed positions. Consequently, when the bridge is closed or open, any forces transmitted through the rod 13 are firmly resisted by said guide portions 18, 19 and the bridge is held solidly in said positions. Moreover, because of the inclination of the portions 18, 19 relative to the horizontal portions of the guide members 17, the bridge swinging movement imparted to the rod 13 by shifting of the rack bar 15 along said guide members obviously is such as to slowly initiate opening and closing movements of the bridge and gradually to reduce the speed of the bridge as it approaches open and closed positions. As shown, each guide member 17 comprises a medial portion and a pair of end portions one of which latter extends 30 above and beyond one end of the medial portion, and is connected therewith by the inclined portion 18, and the other of which extends below and beyond the other end of said medial portion and is connected therewith by the inclined portion 19. Thereby, as distinguished from a known construction involving the use of guide members of generally S-shape in which the end portions are turned backwardly upon the medial portion above and below the latter, instead of 35 being extended "beyond" the ends of the medial portion as in the present case, the present guide members are, comparatively, of materially less over-all height or depth and therefore may be mounted in the ground below and directly adjacent to the surface on which the sector 11 rolls without extending deeply into the ground; whereas, to mount guide members of the known type mentioned in the ground would mean that the lower portions of the guide members necessarily 40 would be deeply disposed where troubles would be encountered in many instances with underground water. Because of the comparatively shallow depth of the present guide members, such troubles are substantially eliminated.

- The rack bar 15 is driven by a sprocket wheel 20 which may derive its power from an electric motor 21, as shown, or from any other suitable source. In this connection, a feature of the invention resides in locating the sprocket wheel at a point approximately midway between the two inclined portions 18, 19 of the guide members so that the rack bar may be of minimum length and so as to conserve space.
- 10 In the Figures 1 to 3 form of the invention it will be noted that the push-pull rod 13 is pivotally connected with the rack bar 15 coaxially with one of the roller carrying pivot pins which connects adjacent medial links of the rack bar.
- 15 Forces thus are transmitted from the rod 13 to the guide member or members 17 only through the roller or rollers which is or are mounted on said pivot pin. However, as illustrated in Figure 4, the rod 13 may be connected with the rack bar 15 at a point between the ends of one of the medial rack bar links. For example, a plate 22 may be secured to a medial link and the rod may be pivoted to said plate as shown, in which event forces are transmitted from the rod 13 to the guide member or members 17 through the rollers at both ends of said link.
- 20
- 25

It is not essential that the rack bar 15 be of the flexible type illustrated in Figures 1 to 4. On the contrary, a rigid rack bar may be employed as illustrated in Figures 5 to 7. In that event, the push-pull rod is pivotally connected to one end of the rigid rack bar 15a and the bar is provided only at said end with a roller or rollers 16a preferably coaxial with the pivotal connection of the push-pull rod with the rack bar and operating in a guide member or members 17a which to all intents and purposes may duplicate the guide members previously described. At a point spaced beyond the inclined portion 18a of the guide member 17a the rack bar is guided for movement in a suitable guide 23 and at this point is located the rack driving sprocket wheel 20a.

40 In each of the forms of the invention there may be employed only a single push-pull rod 13 and associated rack bar and guide means therefore, or two or more push-pull rods and associated rack bars and guide means therefor may be provided at points spaced transversely of the bridge. Moreover, while the drawings illustrate that the rack bar in each instance has associated therewith two guide members 17, one to either side of the rack bar, this is not essential since, obviously, only a single guide member may be employed in connection with any given rack bar.

45 From the foregoing description considered in connection with the drawings it is believed that the construction, operation and advantages of the invention will be clearly understood. It is pointed out, however, that the invention may be embodied in various structures other than those

5 illustrated within the spirit and scope thereof as defined in the appended claims.

I claim:

1. In combination with a bridge of the bascule type having a sector at one end thereof, a horizontal surface on which said sector is rollable to raise and lower the bridge, said surface being substantially level with the ground surface at said end of the bridge, a push-pull operating rod pivotally connected at one end to the bridge, a 10 rack bar to which said operating rod is pivotally connected at its other end, a guide member for said rack bar comprising a medial portion and a pair of end portions one of which latter extends above and beyond one end of the medial 15 portion and the other of which extends below and beyond the other end of said medial portion, said medial and end portions being substantially horizontally disposed, and portions inclined to the horizontal connecting said end portions with 20 said medial portion and disposed, respectively, in alignment with and at substantially right angles to the push-pull rod when the bridge is in open and closed positions, said guide means being mounted in the ground below and directly adjacent to the surface on which the bridge sector is rollable whereby forces imposed on said guide means by the push-pull operating rod are transmitted to the ground, and means to drive said 25 rack bar.

30

2. The combination as set forth in claim 1 in which the rack bar is rigid and in which the push-pull operating rod is connected to one end thereof.

3. In combination with a swinging bridge of 35 the bascule type, a push-pull operating rod pivotally connected at one end to the bridge, a rack bar to which said operating rod is pivotally connected at its other end, a guide member for said rack bar comprising a medial portion and a pair 40 of end portions one of which latter extends above and beyond one end of the medial portion and the other of which extends below and beyond the other end of said medial portion, said medial and end portions being substantially horizontally disposed, and portions inclined to the horizontal connecting said end portions with said medial 45 portion and disposed, respectively, in alignment with and at substantially right angles to the push-pull rod when the bridge is in open and closed 50 positions, said guide means being mounted in the ground below and directly adjacent to the road surface of which the bridge when lowered forms a continuation, whereby forces imposed on said guide means by the push-pull operating rod 55 are transmitted to the ground, and means to drive said rack bar.

4. The combination, as set forth in claim 3 in which the rack bar is rigid and in which the push-pull operating rod is connected to one end 60 thereof.

HEINRICH BREITWIESER.
